US00D973551S

(12) **United States Design Patent** (10) **Patent No.:** **US D973,551 S**
(45) **Date of Patent:** **** Dec. 27, 2022**

(54) **BICYCLE PEDAL**

(71) Applicant: **NING BO QI YING SPORTS EQUIPMENT CO., LTD.**, Ning Bo (CN)

(72) Inventor: **Yong Yao**, Ning Bo (CN)

(73) Assignee: **NING BO QI YING SPORTS EQUIPMENT CO., LTD.**, Ning Bo (CN)

(**) Term: **15 Years**

(21) Appl. No.: **29/788,429**

(22) Filed: **May 25, 2021**

(30) **Foreign Application Priority Data**

May 12, 2021 (CN) 202130281650.9

(51) **LOC (13) Cl.** **12-11**

(52) **U.S. Cl.**

USPC **D12/125**

(58) **Field of Classification Search**

USPC D12/111–113, 125; 74/560, 594.1–594.6;

296/75

CPC B62J 25/00; B62M 3/08; Y10T 74/217;

B60N 3/063

See application file for complete search history.
